UNITED STATES PATENT OFFICE

FREDERICK E. DAYES, OF BROOKLYN, NEW YORK, ASSIGNOR TO AMERICAN CAR AND FOUNDRY COMPANY, OF NEW YORK, N. Y., A CORPORATION OF NEW JERSEY

VEHICLE ROOF STRUCTURE

Application filed September 18, 1924. Serial No. 738,437.

Reference is had to the accompanying drawings which illustrate the preferred form of the invention, though it is to be understood that the invention is not limited to the exact details of construction shown and described, as it is obvious that various modifications thereof within the scope of the claims will occur to persons skilled in the art.

10 In said drawings:

Fig. 1 is a broken central longitudinal vertical section of the upper portion of a double deck bus equipped with a top constructed in accordance with this invention;

15 Fig. 2 is a broken top plan view of the structure shown in Fig. 1 with a portion of the upper deck roof or top removed;

20 Fig. 2^a is a partial top plan view showing a modified construction of upper deck roof, part of the roof covering being broken away;

Fig. 3 is a partial vertical transverse section taken on the line 3—3 of Fig. 1;

Fig. 4 is a vertical transverse section taken on the line 4—4 of Fig. 2;

25 Figs. 5 and 6 are vertical longitudinal sections taken on the lines 5—5 and 6—6, respectively, of Fig. 2;

Fig. 7 is a vertical transverse section taken on the line 7—7 of Fig. 2;

30 Fig. 8 is a detail view in elevation showing the connection of the supporting brackets and the monitor supporting bows and the stops which limit the lowering of the bows; and

35 Figs. 9 and 10 are sections taken on lines 9—9 and 10—10, respectively of Fig. 8.

It is an object of this invention to provide an improved upper deck structure for vehicles, and more particularly to provide an improved cover or roof for the upper decks of vehicles which will permit the vehicle to pass freely beneath such obstructions as overhead trolley wires and elevated railroad structures and which is so constructed as to provide

40 full protection to passengers standing in the upper deck aisle. It is also an object of this invention to provide a cover or roof of the type described which will completely cover the upper deck so as to permit of the full use of the upper deck in bad or cold weather

and which will permit of the upper deck being changed to substantially an open upper deck. It is also an object of this invention to provide a cover or roof of the type described which may be readily changed to suit 55 the weather or operating conditions; which is of simple and durable construction; and which may be readily and economically applied to old as well as to new buses.

In the drawings, the invention is shown 60 applied to a double deck bus having the usual lower deck or body structure 1 which

supports the usual roof or cover 2 for the lower deck which, in this construction, carries a floor 3 for the upper deck. The upper 65 deck is provided with side walls 4 and front and rear walls 5 and 6, respectively, each, in the construction shown, being provided with windows 7 which may be lowered into the window pockets 8 in the walls. The side 70 walls 4 have at their tops side plates 9 to

which are secured the carlines 10 which extend upwardly and inwardly from the side plates 9 and have their inner ends secured to purlins 11 which extend from the front end 75 plate 12 to the rear end plate 13 and are secured thereto, one of said purlins being bent outwardly at the rear of the vehicle to provide clearance over the stairs connecting the upper and lower decks. The purlins 11 80 and the inner ends of the carlines 10 are supported by rods 14 which are secured to the inner or aisle ends 15 of seats 16 and to the purlins 11. At opposite sides of the vehicle at the ends are the permanent cover or 85

roof portions 17, 18, 19 and 20, respectively, which extend from the end plates 12 and 13 to carlines 10 situated a short distance from the ends of the vehicle and from the side plates 9 to the adjacent purlins 11 leaving 90 between the purlins 11 an opening 43 over the center aisle which is not covered by the permanent roof portions.

It will be noted that the purlins 11 are in each case placed slightly outwardly from the aisle ends of the seats 16 and that the carlines 10 are placed above the seats 16 at a sufficient height to provide clearance above the head of the average passenger when seated but are placed too low to provide clear- 100

ance above the head of the average passenger when standing.

In the construction shown in Fig. 2 the openings between the permanent roof sections 18 and 20 and 17 and 19, respectively, are closed by flexible covers or curtains 21 of suitable waterproofed material which are secured at their inner edges to the purlins 11 and which extend from the purlins 11 to the side rails 9 and overlap the permanent roof portions. The covers 21 are supported in between the carlines 10 by slats 22 which rest upon the carlines 10 and the permanent roof sections and are secured to the covers or curtains 21 by straps or loops 23 of any desired material. The curtains 21 may be rolled, as shown in dotted lines in Fig. 3, so as to leave the spaces between the permanent roof portions open. The curtains 21 may have their outer edges secured to the side plates 9 in any desired manner and when so secured they form, with the adjacent permanent roof portions, roof sections which extend from end to end along each side of the vehicle and are separated by a space slightly wider than the aisle between the rows of seats.

In the modified structure shown in Fig. 2 certain of the carlines are made wide so that they form small permanent roof portions 24 which are spaced from the end roof portions 18 and 20 and extend from the side walls to the purlins 11. In this construction each of the curtains or covers 21' extends only between an end portion and the adjacent permanent roof portion 24 or from one permanent roof portion 24 to another. Except for being made shorter so as to render them more readily rolled, the construction of the curtains 21' is the same as shown in Figs. 2 and 3.

To the purlins 11 there are secured at suitable regular intervals brackets 25 having projecting lugs 26. To the brackets 25 bows 29 are secured by bolts 27 which pass through openings in the bow end pieces 28. The bows 29 extend between brackets 25 secured to the purlins 11 on opposite sides of the center aisle and when raised are high enough to clear the heads of passengers standing in the aisle. The bows 29 are connected at their centers by a wood strip 30 which extends from the first to the last bow and is connected to the bows by straps 31 which surround the bows and have outwardly projecting flanges 32 secured to the strip 30 by the bolts 33, the strip being maintained centrally of the bows by collars 34 secured to the bows.

Carried by the bows 29 and secured at its edges to the purlins 11 is a flexible top or cover 35 of suitable woven waterproofed material which extends from end to end of the vehicle and is secured at its front and rear ends to the front and rear end plates 12 and 13, respectively, and at its sides to the pur-

lins 11, the cover 35 being slightly extended on one side at the rear to form an extension 36 which covers over the stairway between the two decks. The cover 35 may be secured to the end rails and purlins in any desired manner as by the bolts 37. The cover 35 is connected to the bows 29 by loops 38 of the same material which pass around the bows 29 and have both ends secured to the cover 35, the loops 38 being secured to the cover so as to permit the bows to travel freely in raising and lowering the cover. The cover 35 and bows 29 form a monitor that can be lowered to reduce the clearance necessary for the passage of the vehicle beneath an obstruction and then raised to provide a cover over the aisle of ample height to permit passengers in the aisle to stand erect. These changes, however, need involve no disturbance of upper deck passengers in their seats.

To operate the bows to raise and lower the cover 35 there are secured to the front bow 29 extensible links 39 having pin and slot connections 40 at one end with the front bow 29 and pivotally connected at their other ends to levers 41 formed integral with quadrants 45 and rotatably mounted on studs 42 fixed in brackets 44 secured to the end plate 12 and the purlins 11. The quadrants 45 are driven by pinions 46 fixed on a shaft 47 journaled in bearings 48 in the brackets 44. The shaft 47 is operated by means of a motor 51 supported from a frame carried by a purlin 11 and a side plate 9. The shaft of the motor has a worm 52 which engages with the worm wheel 53 fixed on the shaft 54, journaled in the brackets 44 and 50 and carrying a pinion 49 which engages a gear 55 fixed on the shaft 47. The motor is controlled in any desired manner by either the conductor or the driver of the vehicle.

In the operation of this device, assuming the bows to be in the raised position, operating the motor 51 in one direction will operate the levers 41 causing the links 39 to travel rearwardly to the limit of their pin and slot connection with the bow 29 whereupon the bows 29 will be operated and through their engagement with the loops 38 will bring the cover 35 down to substantially the level of the side roof sections, the movement of the bows being limited by engagement of the stops 60 on the bow end pieces 28 with the lugs 26 on the brackets 25. Operating the motor 51 in the opposite direction will operate the levers 41 in the opposite direction causing the links 39 to travel in the opposite direction to the full extent of their pin and slot connection with the bows 29 whereupon the bows will be operated and through their engagement with the top 35 and the connection with the top through the straps 38 will raise the top to the position shown in Fig. 1, the engagement of the end bow 29 with the end of the pin and slot connection 40 during the raising

and the lowering of the bows 29 being cushioned by springs 66. As the top in its lowered position engages with the levers 41 protection strips 65 are secured to the top.

5. What is claimed is:

1. An upper deck structure for vehicles comprising side walls, seats separated by a center aisle, roof sections extending inwardly from said side walls to adjacent the center aisle, bows pivotally mounted on said roof sections, means connecting said bows, links connected to one of said bows, operating levers connected to said links, means to operate said levers and a flexible covering for the center aisle carried by said bows and secured to said roof sections.
2. A collapsible monitor for vehicle roofs comprising a plurality of pivotally supported parallel bows, a flexible cover carried by said bows, elongated flexible loops connecting said cover and bows, means connecting said bows to raise and lower said bows together, links connected to opposite sides of an end bow, crank arms connected to said links and a shaft for operating said crank arms.

3. A collapsible monitor for vehicle roofs comprising a plurality of pivotally supported parallel bows, a flexible cover carried by said bows and having its edges secured in position, means loosely connecting said cover and bows, links connected to an end bow, cranks connected to said links, operating means for said cranks and rigid connections between said bows.

4. A vehicle roof structure comprising separated rigid roof sections and a collapsible monitor interposed between said sections and comprising bows pivotally connected to the sections, means connecting the bows operating the same to turn downwardly as a unit into a position substantially parallel with the roof sections and further operating the bows to turn upwardly in like manner into angular relation with the roof sections, and a flexible covering fixedly secured to the roof sections and extending over and operatively connected to the bows and movable therewith.

5. A vehicle roof structure comprising spaced rigid roof sections connected together at one end and a collapsible monitor interposed between said sections and comprising bows pivotally connected to the sections, means connecting the bows operating the same to turn downwardly as a unit into a position substantially parallel with the sections and further operating the bows to turn upwardly in like manner into angular relation with the sections, and a flexible covering fixedly secured to adjacent sides and the connected end portion of said sections and extending over and operatively connected to the bows and movable therewith.

6. A vehicle roof structure comprising spaced rigid roof sections connected together at either end, and a collapsible monitor inter-

posed between said sections and comprising bows pivotally connected to the sections, means connecting the bows operating the same to turn downwardly as a unit into a position substantially parallel with the sections and further operating the bows to turn upwardly in like manner into angular relation with the sections, and a flexible covering fixedly secured to adjacent sides and to the opposite end portions of the sections and extending over and operatively connected to the bows and movable therewith.

7. In a vehicle of the class described, a body having an upper deck and rows of seats defining an intervening aisle, a roof for the upper deck comprising separated sections disposed over the rows of seats, supports for the sections converging downwardly from the inner sides thereof to the inner end portions of said seats, and a collapsible monitor disposed over the aisle and including a flexible covering fixedly secured to the said roof sections.

8. In a vehicle of the kind described, a body having an upper deck and rows of seats defining an intervening aisle, a roof for the upper deck comprising separated frame sections disposed over the rows of seats, supports for the said sections converging downwardly from the inner sides thereof to the inner end portions of the seats, flexible coverings for the said frames adapted to be extended over the frames and further adapted to be folded upon the frames to afford a view of the exterior, and a flexible monitor disposed over the aisle and including a flexible covering fixedly secured to adjacent sides of said frames.

9. The combination with a motor bus having an upper deck provided with an open aisle and top sections at each side of said aisle, of a collapsible inverted trough-shaped cover for said aisle including a plurality of bows extending transversely of said aisle and having leg portions pivoted on the top sections, a bar pivotally connected to said bows at approximately the median line thereof, and a flexible covering for the bows slidably connected to the bar and rigidly secured to said top sections.

10. The combination with a motor bus having an upper deck provided with an open aisle, and longitudinally extending top sections at each side of said aisle, of a covering of flexible material having its longitudinal edge portions secured to said top sections and having an intermediate portion movable vertically above said aisle, and supporting means for the intermediate vertically movable portion including means movable relative to said covering and longitudinally of said aisle.

11. The combination with a motor bus having an upper deck provided with an open aisle, and longitudinally extending top sections at each side of said aisle, of a covering

for said aisle comprising a strip of flexible material having its longitudinal edge portions anchored upon said top sections and having an intermediate portion movable rectilinearly above said aisle, and supporting means for said covering having portions slideable longitudinally thereof and having other portions pivotally mounted on said top sections.

- 10 12. In combination with a motor bus having an upper deck provided with an open aisle and top sections on each side of said aisle arranged above the deck at a height sufficient to accommodate seated passengers, a collapsible covering over said aisle having an intermediate portion normally arranged at a height sufficient to accommodate standing passengers and its longitudinal side edges secured to the before-mentioned top sections, and supporting means for said flexible covering, including means movable relative to said covering and longitudinally of the aisle.

In witness whereof I have hereunto set my hand.

25 FREDERICK E. DAYES.
